MONEY CLIP OR SIMILAR ARTICLE

William F. Kraemer, Pasadena, Calif., assignor to J. A. Meyers and Company, Inc., Los Angeles, Calif., a corporation of California

Application April 19, 1956, Serial No. 41,137

Term of patent 14 years

(Cl. D17—3)

Fig 1

Fig. 2 is a top plan view thereof;

Fig. 3 is a perspective view thereof; and

Fig. 4 is a view similar to Fig. 1 but with the money clip shown in open position.

I claim:

The ornamental design for a money clip or similar article, substantially as shown and described.
